UNITED STATES PATENT OFFICE.

HARRY L. SNOW, OF REESEVILLE, WISCONSIN.

PRINTING-MACHINE.

SPECIFICATION forming part of Letters Patent No. 404,058, dated May 28, 1889.

Application filed May 23, 1888. Serial No. 274,838. (No model.)

To all whom it may concern:

Be it known that I, HARRY L. SNOW, a citizen of the United States, residing at Reeseville, in the county of Dodge and State of Wisconsin, have invented a new and useful Improvement 5 in Printing-Machines, of which the following is a specification,

My invention relates to an improvement in printing-presses; and it consists in the peculiar construction and combination of devices, that will be more fully set forth hereinafter, and particularly pointed out in the claims.

In the accompanying drawings, Figure 1 is a perspective view of a printing-press embodying my improvements, showing the same in position, with the tympan folded down over the form and the impression-roller in the act of passing over the tympan. Fig. 2 is a side elevation of the same, showing the impression-roller at one end of its stroke or longitudinal movement and showing the tympan raised. Fig. 3 is a top plan view of my improved printing-press. Fig. 4 is a vertical transverse sectional view of the same. Fig. 25 5 is a detail horizontal sectional view taken on the line *xx* of Fig. 4.

A represents the bed of the press, which is of suitable length, width, and thickness, and is supported at suitable elevation by means 30 of legs B, which depend from the corners thereof. On the upper side of the bed, at the ends thereof, are transverse bars C, which form flanges to secure the chase (not shown) on the bed. On opposite sides of the bed are secured two pairs of longitudinal guide-bars, D, which have grooves E' formed in their opposing sides. From one of the upper guide-bars D extends a vertical longitudinal flange or bar, E, which rises above the face of the bed to a suitable height and forms one side of the bed, the said flange-bar having teeth or spurs F on its upper edge. The length of the said flange-bar is equal to the length of the guide-bars D, and projects beyond the 45 ends of the bed with the said guide-bars.

G represents a pair of slide-rods, which are provided on their upper and lower sides with flanges which fit in the grooves E', and are thereby adapted to slide back and forth between the bars D. The said slide-bars G have rack-teeth H on their lower edges. Secured to the outer sides of the slide-bars, at the cen-

ters of the same, are the lower ends of a pair of vertical standards, I, which have vertical slots K of suitable length in their upper ends. On the front and rear sides of the said slots are formed guiding-tongues L, which engage corresponding grooves that are formed in opposite edges of a pair of bearing-blocks, M.

N represents an impression roller or cylinder, which is arranged transversely between the standards I, and has spindles at its ends, which are journaled in the blocks M. At one end of the said cylinder or impression-roller is a spur-wheel, O, the teeth of which engage 60 the rack-teeth F on one side of the bed.

P represents a pair of adjusting-screws, which are arranged in the lower portions of the slots K and have their upper ends bearing against the lower sides of the blocks M. The said adjusting-screws are provided with 70 adjusting-nuts R, by means of which the blocks M may be lowered, thereby adapting the impression-roller to be vertically adjusted, as will be readily understood.

Coiled extensible springs S bear upon the upper side of the blocks M, and are engaged at their upper ends by set-screws T, which work in threaded openings in the upper ends of the standards. By means of these set-screws and springs the pressure exerted by 80 the impression-roller on the form may be regulated, as will be hereinafter set forth.

U represents a transverse shaft, which is journaled in suitable bearings, V, under the 85 center of the bed. The said shaft has a crank, W, at one end, by means of which it may be rotated, and rigidly attached to the said shaft is a pair of spur-wheels, X, the upper sides of which extend through openings in the centers 90 of the lower guide-bars D and engage the rack-teeth H on the lower sides of the slide-bars G.

From the foregoing description it will be understood that by rotating the shaft U the 95 guide-bars carrying the standards I may be moved longitudinally in either direction, so as to cause the impression-roller to pass over the bed from end to end thereof, and that, inasmuch as the said impression-roller is geared 100 to the rack F by the wheel O, the impression-roller will be caused to rotate as it moves over the bed.

At one end of the bed, on the outer side of

one of the cross-bars C, are a pair of vertical standards, Y.

Z represents a tympan-frame, which is adapted to cover the bed, and comprises a pair of side bars, A', connected at one end and near the opposite ends by a pair of cross-bars, B', which are adapted to bear upon the upper edges of the flanges C when the tympan is arranged over the bed. An impression-blanket, C', is stretched between the bars of the tympan-frame and secured thereto. The ends of the bars A', which project beyond one of the cross-bars B', bear against the standards Y and are pivoted there-to, the extreme ends of the said bars being adapted to come in contact with the outer sides of one of the flange-bars C when the tympan is raised, so as to support the latter in the position indicated in Fig. 2.

20 The operation of my invention is as follows: The form is arranged on the bed in the usual manner and inked by a hand-roller. The sheet of paper to be printed is secured in the correct position on the inner side of the tympan and the latter is turned downward on the form, so as to cause the paper to bear upon the faces of the type, and the operator then turns the crank-shaft, so as to cause the slide-bars to move the standards I, and consequently cause the impression cylinder or roller to pass over the tympan, and thereby impress the sheet of paper upon the face of the form and print the same. When the roller has passed beyond the opposite end of the form, 35 the tympan is raised, a new sheet fed thereto, the printed sheet being previously removed therefrom, and the form is re-inked. The tympan is then turned downward thereon, and the roller is then passed over the form in the opposite direction from that previously described.

40 A printing-press thus constructed is exceedingly compact, is strong and durable, may be manufactured at a small cost, and is capable of doing very superior work, and may be easily and rapidly operated.

Having thus described my invention, I claim—

1. The combination of the bed having the 50 rack-bar F and the guide-bars D, with the slide-bars arranged in the guide-bars and having the racks H, the standards secured to the slide-bars, the impression-cylinder journaled in the said standards and having the 55 spur-wheel engaging the rack F, and the oper-

ating-shaft having the wheels X, engaging the racks H, for the purpose set forth, substantially as described.

2. The combination of the bed or frame having the longitudinal guide-bars provided with grooves in their adjacent faces, the slide-bars guided between said guide-bars and having flanges fitting in the grooves thereof, the lower flanges being provided with teeth or racks, a shaft journaled transversely under 60 the bed or frame, and pinions upon said shaft extending through slots or openings in the guide-bars and meshing with the racks upon the slide-bars, substantially as set forth.

3. The combination of the bed or frame 70 having the longitudinal rack-bar F on its upper side, the guide-bars D D, arranged in pairs at each side of the frame, and standards Z at one end of the latter, the tympan-frame pivoted to said standards and having 75 rearward-projecting arms, the rack-bars sliding longitudinally between the guide-bars, the standards secured to said sliding rack-bars and having vertical slots, the impression-cylinder journaled in boxes vertically adjustable in said slots, springs forcing the said cylinder in a downward direction, a shaft 80 journaled transversely under the bed or frame and having an operating-crank, pinions upon said shaft meshing with the longitudinally-sliding rack-bars, and a gear-wheel upon the cylinder-shaft meshing with the longitudinal rack-bar upon the upper side of the bed or frame, substantially as and for the purpose 85 set forth.

4. The printing-press comprising the bed having the rack-bar F and guide-bars D on its sides and the standards Y at one end, the slide-bars arranged in the guide-bars and having the racks H, the standards I, secured 90 to the slide-bars, the impression-cylinder journaled in the standards I and having the spur-wheel engaging the rack, the tympan-frame pivoted at one end to the standards Y, and the operating-shafts having the wheels X, engaging racks on the slide-bars, substantially as set forth.

In testimony that I claim the foregoing as my own I have hereto affixed my signature in presence of two witnesses.

HARRY L. SNOW.
